ARRANGEMENT FOR EXTRACTING METAL BODIES FROM WEBS OF TEXTILE MATERIALS

Hubert Duesberg, Brussels, Belgium; vested in the Alien Property Custodian

Application April 18, 1940, Serial No. 330,410
In Belgium April 19, 1939

4 Claims. (Cl. 19—98)

1

In the treatment of textile materials by means of cards, it frequently happens that the web of textile material contains foreign bodies, in particular metal bodies, such as doffer teeth. The presence of these foreign bodies considerably interferes with the working to which the web is subsequently subjected and in particular when the actual doffer is followed by an arrangement intended to eliminate by calendering the impurities such as hard ends, loose fibres and the like, which the aforesaid web may contain.

The calendering of the web is carried out through the intermediary of two ground rollers called calender cylinders, between which the web passes.

The metal bodies, which are of harder composition than the ground rollers, score these rollers and gradually reduce their efficacy. It is then necessary to have these rollers ground, in order to restore thereto the qualities necessary for the work which they are to accomplish, which entails a loss of time and money and a loss of output, since the removal of the calender rollers necessitates temporarily placing the machine out of service.

In order to overcome this disadvantage, it is proposed in accordance with the invention to submit the web of textile material to a magnetic action produced by windings in a casing arranged near the doffer and under the part where the web leaves it before introduction of the web between the calender rollers, this magnetic action having the effect of freeing the web from any metal impurity which may impair the operation of the said rollers.

Further features of the invention will appear from the following description.

The accompanying drawings show by way of example an arrangement for carrying the method into effect.

Figure 1 is a view in perspective, partly broken away, of a particular form of the magnetic separator;

Figure 2 is a diagrammatic view of the winding with which the said separator is provided;

Figure 3 shows the application of the said separator to a carding installation.

The web 2 (shown in dotted lines) according to the invention, which is composed of textile materials, is fed onto the doffer 3 and is detached from the latter by the action of a vibrating knife or comb 4, to which a constant oscillatory movement is imparted. When the web leaves the doffer 3, it is submitted to the magnetic action of a casing 5 and is then brought onto an endless

2 belt 6 or any other similar conveyor device, whence it passes between calendering rollers 6 and 7 located to the right of the belt 5. The web 2 frequently contains card teeth removed from the carding devices (drum, comb and the like), which metal particles can score the calender rollers in passing therebetween and rapidly render them unserviceable.

In order to prevent such injury to the rollers, it is proposed according to the invention to mount a magnetic separator 8 extending across the entire width of and below the textile web, at a point between the doffer 3 and the calender rollers 6 and 7. By the action of the separator the aforesaid web is freed from any metal bodies. This magnetic separator 8 may be constituted by an electromagnet fed either with direct or alternating current, or it may be constituted by a permanent magnet.

20 The magnetic separator 8 shown in Figure 1 comprises a casing, the side walls 10 and 11 of which are constituted by a sheet of soft steel about 3 mm. thick. These two sheets disposed obliquely with respect to one another, so as to 15 form a kind of inclined plane, are connected together by a zone 12 of a non-magnetic alloy, commencing at a distance of about 15 mm. from the edge of the said inclined plane. The aforesaid zones extends over a length of about 10 mm. 25 and its composition is, for example, the following:

	Per cent
Lead	50
Tin	49
5% phosphor-tin	1

Inside the said casing is disposed a series winding 14 (see also Figure 2) provided with a circuit breaker, not shown, and fed, for example, at 12 30 volts.

This magnetic separator is disposed (see Figure 3) in the neighborhood of the vibrating knife or comb 4 in such manner that its face 10 is situated at about 25 mm. from the periphery of the doffer 3. In addition, this separator is so mounted that its rounded edge 16 is situated in the neighbourhood of the web 2 of textile material, but without the latter touching the said edge.

35 It will be understood that the invention is not limited to the embodiment described by way of example but that it covers any embodiment falling within the scope of the following claims.

What I claim is:

1. A textile carding machine comprising a

3. A textile carding machine comprising a doffer, a vibrating comb for detaching a web of textile fibres from the doffer, a casing provided with electro-magnetic windings arranged near the comb and beneath the web for attracting metal particles through and from the web, conveyor means for the web, and calender rolls to which the web is conveyed by said means.

2. A textile carding machine comprising a doffer, a vibrating comb for detaching a web of textile fibres from the doffer, a casing provided with electro-magnetic windings arranged near the comb and beneath the web for attracting metal particles through and from the web, an inclined surface on said casing for receiving the metal particles, conveyor means for the web, and calender rolls to which the web is conveyed by said means.

3. A textile carding machine comprising a doffer, a vibrating comb for detaching a web of textile fibres from the doffer, a casing provided with electro-magnetic windings arranged near the comb and beneath the web for attracting metal particles through and from the web, an inclined surface comprising a non-magnetic part between the two magnetic poles forming the upper part of said casing which receives the metal particles, conveyor means for the web, and calender rolls to which the web is conveyed by said means.

4. A textile carding machine comprising a doffer, a vibrating comb for detaching a web of textile fibres from the doffer, a casing provided with electro-magnetic windings arranged near the comb and beneath the web for attracting

metal particles through and from the web, an inclined surface comprising a non-magnetic part between the two magnetic poles forming the upper part of said casing which receives the metal particles said non-magnetic part being composed of lead 50%, tin 40% and phosphor tin 1%, conveyor means for the web, and calender rolls to which the web is conveyed by said means.
